FABRIC ABRADING TESTER

Robert L. Hood, Stamford, Conn., assignor to
 American Cyanamid Company, New York,
 N. Y., a corporation of Maine

Application January 19, 1945, Serial No. 573,530

1 Claim. (Cl. 73-7)

1 The present invention relates to an automatic cut-off device for determining the resistance of textile fabrics to abrasion.

There is on the market today a fabric abrasion tester in which a circular sample of the fabric undergoing test is clamped onto a motor-driven turntable and the sample rotated beneath a pair of rubber-tired abrading rollers resting thereon. The axes of the two rollers are arranged to one side of the center of the rotating turntable so that as the fabric is rotated beneath the rollers, the latter produce a scraping, abrading action on the fabric. A counting mechanism is provided so that the number of rotations of the fabric on the turntable occurring before the desired degree of abrasion takes place may be observed. In the operation of this instrument the operator must closely observe the fabric and shut off the machine upon failure of the former.

The principal object of the present invention is to provide an automatic cut-off for devices of this character which will not require constant visual observance by the operator, but on the other hand will automatically terminate the test. Such an improvement is of decided advantage in this art in that the human element is eliminated, thus tending to make tests more uniform and in addition releases manpower for other useful work, as a single operator may have several such tests in progress simultaneously, not possible heretofore.

The invention contemplates, therefore, an instrument of the type described in combination with a hook element lightly resting upon the sample of fabric undergoing test, and so arranged that upon failure of the fabric under the action of the abrading roller, which failure manifests itself by a hole formed in the fabric, the hook will catch therein and further rotation of the turntable will cause the hook to trip a switch which interrupts the current to the turntable motor.

In the drawings:

Fig. 1 is a general perspective view of the combination of the present invention, and

Fig. 2 is a diagrammatic layout showing the essential elements and the wiring diagram used to interrupt the current to the motor.

Referring now with particularity to the drawings, the abrading instrument is shown to include a housing 1, within which is located an electric motor (not shown) but which is indicated at 2 in Fig. 2. This motor is arranged to rotate a turntable 3 in say a counter-clockwise direction and at any desired speed.

2 Mounted upon the turntable is a sample 4 of the textile fabric undergoing test, which is securely held by means of a peripheral two-piece clamp 5 and 6, secured together as by a pair of nuts 7, only one of which is shown. The sample is secured to the turntable at the center portion thereof by means of a disc 8 and a knurled thumbscrew 9.

Also secured to the casing 1 in bearings 10, is a weighted arm 11 which may oscillate about trunnions 12.

The arm 11 is provided with a pair of rubber-tired rollers 13 and 14, each of which has an independent stub axle 15 and 16, secured to the arm. The axes of the axles 15 and 16 are in alignment and to one side of the axis of rotation of the turntable 3.

Thus a sample of material undergoing test being clamped to the turntable and the motor started, the weight of the arm 11 will cause the rubber-tired rollers 13 and 14 to bear upon the sample and be driven thereby in opposite directions with a scraping, abrading action. A counting mechanism 17 is built into the machine so as to record the rotations of the turntable required to produce failure in the sample undergoing test.

An automatic cut-off mechanism is provided which includes a hook 18 of wire or other suitable material resting upon the surface of the fabric undergoing test and so arranged as to catch in any hole or tear produced in the fabric by the abrading rollers upon failure of the fabric. This hook is secured in a spindle 19 pivoted as at 20 to the upper end of arm 21.

Upon failure of the fabric, the hook 18 catches into a tear or hole therein and further rotation of the turntable pulls the spindle 19 to the right (Fig. 2) thus actuating a micro-switch 22, which, through suitable electrical connections, operates a release 23, which opens the line supplying current to the motor 2, thus stopping progress of the test automatically. Through suitable mechanism, the motor may not be started again until the button 24 is pressed, which operates relay 25 to re-set the relay 23.

Upon completion of a test and where it is desired to replace the fabric which has failed with another fresh specimen, the spindle 19 may be raised about its pivot 20 to facilitate changing of the specimen.

While the invention has been shown and described with reference to particular embodiments, yet it is not to be limited thereto but is to be restricted only by the scope of the claim.

55 What is claimed is:

In a fabric abrading machine having a turn-table adapted to receive a sample of fabric to be tested, an electric motor for driving the same, means to supply current thereto, an abrading roller having a friction surface adapted to rest on the sample of fabric to one side of the turn-table center and be driven thereby, the improvement which includes a circuit interrupting device for the motor and a hook connected therewith, the hook being adapted to rest on the surface of the fabric being tested so that upon failure of the fabric under the action of the abrading roller, the hook will catch in the fabric and further movement of the turntable will, through the

instrumentality of the hook, trip the circuit interruption means and stop the turntable driving motor.
